Primary Examiner — Ricky Pham*(74) Attorney, Agent, or Firm* — Kintner IP, LLC; Mary Frances Ludwig(57) **CLAIM**

The ornamental design for a spoon, as shown and described.

DESCRIPTION

FIG. 1 is a perspective view of a spoon showing my new design;

FIG. 2 is a top plan view thereof;

FIG. 3 is a left side elevation view thereof, the right side being a mirror image;

FIG. 4 is a bottom plan view thereof;

FIG. 5 is a partial sectional view along line 5-5 of FIG. 2; FIG. 6 is a perspective view of a second embodiment of the spoon;

FIG. 7 is a top plan view of the embodiment of FIG. 6;

FIG. 8 is a left side elevation view of the embodiment of FIG. 6, the right side being a mirror image; and,

FIG. 9 is a bottom plan view of the embodiment of FIG. 6. Elements shown in broken lines form no part of the claimed design.

1 Claim, 4 Drawing Sheets(56)
